UNITED STATES PATENT OFFICE

146,573

DESIGN FOR A TANK TYPE SUCTION
CLEANER CASINGClarence Karstadt, Glen Ellyn, Ill., assignor to
Birtman Electric Company, a corporation of
IllinoisContinuation of design application Serial No.
120,376, June 28, 1945, which is a continuation
of design application 116,569, November 27,
1944. This application March 8, 1946, Serial
No. 127,232

Term of patent 14 years

(Cl. D9—2)

To all whom it may concern:

Be it known that I, Clarence Karstadt, a citizen of the United States, residing at Glen Ellyn, in the county of Du Page and State of Illinois, have invented a new, original, and ornamental Design for a Tank Type Suction Cleaner Casing, of which the following is a specification, reference being had to the accompanying drawing, forming a part thereof, in which:

Fig. 1 is a side perspective view of a tank type suction cleaner casing, showing my new design. Fig. 2 is a top plan view thereof; and Fig. 3 is a perspective end view thereof.

This is a continuation of my copending application Serial No. D. 120,376, filed June 28, 1945, which was a continuation of application Serial No. D. 116,569, filed November 27, 1944.

I claim:

The ornamental design for a tank type suction cleaner casing, as shown and described.

CLARENCE KARSTADT.
